PROTECTION SYSTEM

Enos Cornwall, Kansas City, Mo.

Application March 22, 1933, Serial No. 662,071

10 Claims. (Cl. 20—1.01)

My invention relates to theft prevention means, and more particularly to a theft prevention system for preventing both daylight and night robberies particularly of safes or similar receptacles. 5 It is a purpose of my invention to provide an electrically operated tear gas device which releases the tear gas upon the movement of a door, such as the door of a safe, out of closing position, said means releasing tear gas both internally of the safe or other receptacle and externally thereof.

It is a further purpose of my invention to provide an apparatus of the above mentioned character that is so constructed that any attempt 15 to disturb the wiring conducting the electric current to the tear gas guns or other discharging apparatus will close the electrical circuit to actuate said tear gas releasing means.

It is another purpose of my invention to provide an apparatus of the above mentioned character in which any number of tear gas releasing means may be provided to be actuated by the closure of the same circuit, each of said tear gas releasing means being provided with a fusible electrical element operating to set off the tear gas.

It is another purpose of my invention to provide a new and improved tear gas discharging means or tear gas gun, which is simple in construction and in which the shell portion of the tear gas cartridge also serves as the barrel portion of the gun, and to provide means for detachably mounting such a combination shell and gun in a suitable holder.

It is another purpose of my invention to provide a tear gas discharging device or gun of the above mentioned character in a suitable holder for directing the same in any desired direction, said holder being provided with means for preventing the discharge of wadding and other solid particles from the gun.

It is a further purpose of my invention to provide a tear gas apparatus comprising a discharging device comprising means for projecting 45 the gas in a plurality of different directions so as to provide a spreading action of the tear gas when this is desired.

It is an important purpose of my invention to provide operating means for discharging said apparatus so constructed and arranged as to prevent accidental discharge of tear gas by said apparatus, this being accomplished by providing an operating means that can only be moved, into position to initiate operation of said apparatus to discharge said tear gas, by a plurality of operations, and which comprises a foot operated controlling member constructed and arranged in such a manner that operation thereof will not cause the operator's body to go through a

motion that might arouse the suspicions of a bandit.

Other objects and advantages of my invention will appear as the description of the drawings proceeds. I desire to have it understood, however, that I do not intend to limit myself to the particular details shown or described, except as defined in the claims. 5

In the drawings:

Fig. 1 is a fragmentary perspective view, partly in section, of my improved theft prevention system as applied to a safe and cashier's cage. 10

Fig. 2 is a top plan view of one of the tear gas discharging means.

Fig. 3 is a side elevation thereof.

Fig. 4 is a bottom plan view thereof, partly broken away.

Fig. 5 is a section taken on the line 5—5 of Fig. 2.

Fig. 6 is a section taken on the line 6—6 of Fig. 5. 20

Fig. 7 is a section taken on the line 7—7 of Fig. 5.

Fig. 8 is a longitudinal sectional view through the combined gun barrel and cartridge. 25

Fig. 9 is a side elevation of the short circuiting means for closing the circuit when the wiring is tampered with.

Fig. 10 is a section taken on the line 10—10 of Fig. 9. 30

Fig. 11 is a horizontal longitudinal sectional view through a tear gas discharge device modified for long range operation.

Fig. 12 is a vertical, longitudinal, sectional view of the device shown in Fig. 11. 35

Fig. 13 is a view in side elevation of a tear gas discharge device particularly adapted for use in position against a wall or in a safe.

Fig. 14 is a longitudinal sectional view of the device shown in Fig. 13. 40

Fig. 15 is a circuit diagram of the apparatus shown in Fig. 1.

Fig. 16 is a side elevation of my improved foot operated controlling device.

Fig. 17 is a top plan view thereof.

Fig. 18 is a longitudinal section thereof.

Fig. 19 is a section taken on the line 19—19 of Fig. 18. 45

Fig. 20 is a section taken on the line 20—20 of Fig. 19, and

Fig. 21 is a fragmentary side view of said controlling device partly broken away, showing the parts in circuit closing position. 50

Referring in detail to the drawings, in Fig. 1 is shown a safe 22, which is provided with a door 23, which is of the usual construction and in said safe at any desired location, preferably near the door and near the bottom thereof, is mounted a holder 24 for a tear gas discharging device. Also mounted within the safe and se- 55

cured to a side wall thereof closely adjacent the door is a switch base 25, which is provided with a spring contact member 26.

Mounted externally of the safe 22 is another holder 27 for a tear gas discharge device, and if desired an additional holder, such as the holder 28, may be provided for a tear gas discharge device, the holder 27 being mounted on the wall 29 and the holder 28 being mounted above a window 10 30 in a partition 31, such as provided on the front of bank cages or cashiers' cages. A battery 32 of suitable design is also provided for operating the tear gas discharge apparatus and a manually operated controlling switch 33 is provided, which 15 is preferably in a secret location and may be provided with a closure 34 to prevent unauthorized operation of the same. If desired, a dummy switch 35 may also be provided, either near the switch 33 or at any other desired point where it 20 might lead the person seeing the same to believe that it controls the protective apparatus.

Referring now to Fig. 8 it will be seen that the tear gas discharge device or tear gas gun comprises a base member 36 in the form of a cap or 25 cup-like member, which has internal threads 37 thereon and which has an opening 38 therethrough, through which a headed, threaded member, such as the screw 39 having the head 40 thereon extends. A shouldered insulating sleeve 30 41 is interposed between the body portion of the fastening member 39 and the metallic base member or cap member 36 with the shoulder thereon engaging the inner face of said cap member 36, and an insulating washer 42 is mounted between 35 the nut 43 and said member 36. A terminal clip 44 is clamped between the nut 43 and the nut 45 on the member 39. One end of a fusible electrical element or fuse wire 46 extends around the member 39 under the head 40 and is clamped 40 between the head 40 and the insulating sleeve 41 in spaced relation to the inner face of the cap member 36. The other end of said fusible element 46 is located under an insulating washer 47, said insulating washer being clamped in position 45 by means of a sleeve-like member 48, which screw threadedly engages the internal threads of the cap member 36, but which is reduced in external diameter so as to permit the tubular member or barrel member 49 of the tear gas discharge device 50 to be received over the same and to have the screw threads 50 on the end thereof engaged with the internal threads 37 on the member 36.

Highly inflammable material producing a large amount of gas, such as gun powder 51, is packed 55 in the bottom of the sleeve-like member around the head 40 of the member 39 and surrounding the fusible element 46, and being confined by means of a pair of disk-like members 52 and 53 of fibrous sheet material, the member 52 being 60 of such size as to fit in the bore of the sleeve 48 and the member 53 to fit the bore of the tubular member 49. The length of the sleeve-like member 48 is preferably such that it will be completely 65 filled by the proper amount of gun powder 51 or similar explosive material, and the member 52.

In preparing the apparatus for use the fusible element is first put in place, the nut 43 being loosened to permit the insertion of the fusible element under the head 40 of the member 39 and 70 being tightened up after said element has been put in place under said head to hold said end in fixed position. The free end of the fusible element 46 is then pushed down against the bottom of the member 36 and the washer 47 is put in 75 place over the same. The sleeve-like member 48

is then screwed down in position. The powder 51 and the disk-like member 52 are then inserted and after this has been done the tubular member or barrel member 49 is screwed into position. The disk-like member 53 of fibrous material is 5 then inserted in the inner end of the member 49 and engages the end wall of the sleeve 48. This is then sealed in position by any suitable sealing material, such as paraffin, which is indicated at 10 55 in Fig. 8, this seal preventing the leakage of any tear gas producing liquid into the sleeve-like member 48 where it might affect the explosive material 51.

A tear gas holder 56 is then inserted in place in the tubular member 49, said tear gas holder being 15 shown as being made in the form of a capsule of frangible material, within which liquid tear gas is contained. If desired the tear gas producing material may be used in solid form. A fibrous disk-like closure member 57 is then inserted in the tubular member and sealing material 58 is applied thereto to seal the outer end of the tubular member 49 thus preventing any 20 accidental leakage of the tear gas producing liquid therefrom. A bead 59 is provided on the 25 exterior of the tubular member 49 between the ends thereof, and forming a rib thereon, and is provided with a notch or interruption therein at 60.

The holder 28 is shown more in detail in Figs. 20 2, 3, 4, 5, 6 and 7, and comprises a body portion 61 having a pair of side flanges 62, and having a transverse rib 63 extending inwardly from the inner face thereof, said rib 63 having a curved 25 notch or recess 64 therein providing a pair of abutments 65 on opposite sides of said curved cut-out portion. Extending forwardly from the transverse rib 63 is a longitudinally extending rib 66, it being clear from Fig. 5 that the rib 66 is integral with the rib 63. The rib 63 is spaced 30 adjacent the middle of the body portion 61, said body portion having a rear wall 67 of similar height to the flanges 62, and a second transverse rib 68 is provided spaced from the rib 63 and 35 similarly shaped, said rib 68 being nearer the 40 back 67 than the rib 63. The curved opening or recess in the central portion of the rib 68 is, however, smaller than that in the rib 63, and the rib 68 is provided with a reinforcement 69, extending 45 rearwardly therefrom to strengthen the same and provide a strong abutment for the rear wall of the cap portion 36 of the load carrying or charge carrying member previously described.

The holder is further provided with a cover member 70 that seats on the flanges 62 and on the 55 edge of the rear wall 67, and which is provided with a pair of transverse ribs 71 and 72 spaced the same distance apart as the ribs 63 and 68. It will be noted that the ribs 63 and the ribs 68 have the portions thereof that face each other 60 extending substantially parallel to each other and substantially perpendicular to the bottom of the body portion. In a similar manner the portions of the ribs 71 and 72 that face each other are 65 substantially parallel and substantially perpendicular to the cover member 70. Abutments are thus provided engaging respectively with the rear wall of the cap 36 and the shoulder formed where the annular edge of the cap 36 projects outwardly from the tubular member 49. The rib 71 is provided with a curved cut-out portion 73, while the rib 72 is substantially straight across. The curvature of the cut-out portions or openings in the ribs 65 and 71 is such as to conform substantially to the curvature of the barrel portion or 70 75

tubular body portion 49 of the charge carrying member, as will be evident from Fig. 6.

The cover member 70 is provided with pairs of projections or lugs 74 thereon that locate the cover relative to the flanges on the body portion. When the charge carrying member comprising the tubular body 49 and the cap 36 is in position in the holder the bead 59 is so positioned that the gap or notch 60 therein receives the rib 66 to prevent rotation of the charge holding member in the holder. The cover member 70 is secured to the body portion 61 by means of a plurality of screw threaded, headed fastening members 75 that extend through suitable openings in the cover and have screw threaded engagement with threaded openings 76 in the body portion 61, said body portion being suitably reinforced to provide the necessary material for anchoring said fastening devices. A pair of threaded, headed fastening members are also extended through openings in the body portion and in the cover, to clamp the holder in position on a suitable support. It will thus be seen that the charge carrying member is held from movement in any direction and from rotation in the holder by the combination of devices described above when the cover member is fixed in position on the body portion of the holder.

The body portion 61 is generally rectangular, but has a forward extension that is of reduced depth, which is connected with the main portion of the body portion 61 by means of an obliquely extending wall portion 79. Said portion of reduced depth forms a forward extension on the body portion 61, and tapers in a forward direction to provide a reduced neck portion thereon at 80, and a head portion 81 that is curved in all directions. The cover member is shaped to conform to the shape of the body portion 61 having an inclined wall portion 82 engaging the wall portion 79 and having a reduced neck portion 83 corresponding to the neck portion 80, and a head portion 84 corresponding to the head portion 81 in curvature and in general characteristics.

When the cover 70 is assembled with the body portion 61 the abutments formed by the wall portions at the neck portions 80 and 83 form a substantially annular inwardly extending rib portion or abutment that holds the forward end portion of the tubular member 49 in fixed position, as will be evident from Fig. 4. It will thus be seen that the discharge end of the tubular member 49 opens into the head portion of the holder made up of the head portion 81 and the head portion 84 at the neck portion formed by the portions 80 and 83 of the body portion and cover member of the holder, respectively. The head portion 81 has an inwardly extending substantially centrally located boss 85 of large cross section, and the head portion 84 of the cover member has a similar boss 86, which aligns with the boss 85. A screw threaded, headed fastening member 87 extends through an opening 88 in the boss 85 and screw threadedly engages in a threaded opening 89 in the boss 86, thus clamping the head portions of the device firmly together with the straight edge portions 90 and 91 of the body portion and cover member in firm engagement.

It will be noted that the boss 85 and the boss 86 each have a pair of inclined diverging faces 92 thereon, facing the opening in the end of the tubular member 49 and that these wall portions 92 tend to deflect the charge after it passes out of the open end of the tubular member 49 laterally

around the boss in opposite directions, the remainder of the boss having a curved wall portion 93 providing a curved passage between the outer wall portions of the heads 81 and 84, which widens somewhat in a lateral direction when the holder is viewed from a position such as that in Fig. 4, and narrows at the extreme forward end of the head portion, this shape of the passage tending to produce a whirling action of the gases generated so that the same will tend to be thrown laterally and outwardly in all directions, due to the centrifugal force as the same tend to pass in a curved path around the boss, causing the gases to be thrown upwardly, laterally and in a forward direction through the slots 94 provided between the head portion 84 on the cover member 70 and the head portion 81 on the body portion 61, said slots having diverging walls so that the slots enlarge toward the front of the holder, said slots terminating short of a central opening 95 in the forward end of the holder, said opening being of greater transverse than vertical dimensions, so as to form a substantially elliptical opening in the front of the device, lugs 96 and 97 being formed on the body portion and cover member respectively, to space the opening 95 from the slots 94, the substantially straight abutting edges of the lugs 96 and 97 engaging when the screw threaded fastening member 87 clamps the parts of the head together. The head portion 84 is provided with a plurality of small openings 98 therein, which are spaced about the head portion 84 in any desired arrangement that is found to be desirable to get the proper projection and diffusion of the gas from the discharging means within the holder.

The bosses 85 and 86 are each provided with a longitudinal slot 99 and a transverse slot 100 intersecting the slot 99 so as to provide a seat for a headed pointed member 101, which may be a tack-like member, which serves as an impaling member for the set of fibrous disk-like members provided in the tubular member 49 and the parts associated therewith. The headed member 101 is merely laid in the slot in the body portion 61, and then when the cover member is put in place it will be held firmly clamped in position between said body portion and cover member. The rear wall 67 of the body portion is provided with an opening 102 therein, through which a conductor cable 103 is adapted to extend, and a boss 104 is provided on the body portion 61 that has a threaded opening therein for receiving a terminal screw 105, the purpose of which will be described below.

The holder shown in Figs. 11 and 12 is made with a body portion 61' that is substantially the same in construction as the body portion 61 previously described, having a similar head portion thereon and the various parts shown in Figs. 11 and 12 corresponding to the parts shown in Figs. 2 to 7 inclusive, are designated by the same reference numerals. The cover member 70' is also made in substantially the same manner as the cover member 70, and the parts that are the same on the cover member 70' as in the cover member 70 are designated by the same reference numerals in Fig. 12 as in Figs. 2 to 7 inclusive. However, the body portion 61' is provided with a boss 85' corresponding to the boss 85, and the cover member with a boss 86' corresponding to the boss 86. The bosses 85' and 86' instead of having flat engaging faces and grooves for receiving an impaling member, are provided with transversely curved tapering grooves 106 and 107, in which is

seated a tapering tubular member 108, which seats against the forward end of the tubular member 49 and is received between the annular inwardly directed ribs formed by the cooperating neck 5 portions 88 and 83 so as to fix the tubular member 108 in position in such a manner as to be an extension of the tubular member 49, the member 108 tapering so as to decrease in diameter in a vertical direction toward the forward end thereof and flaring laterally toward the forward end thereof, as will be evident upon reference to Figs. 11 and 12.

The opening 95' is similar to the opening 95, but corresponds in shape and dimension to the 15 interior end of the tubular member 108, and is provided with a shouldered portion 109 in which the forward end of the member 108 seats to prevent its dislodgement from within the head formed of the head portions 81 on the holder 84 20 on the cover member, respectively. The head portion 84 of the cover member is not provided with any small openings therein, however, as in the form of holder shown in Figs. 2 to 7 inclusive. The holder shown in Figs. 11 and 12 is used to 25 project tear gas to a distant point, causing a gradual scattering, but a pronounced forward projection thereof instead of a wider diffusion thereof, as would be the case with the holder 28, or any other holder that is provided with a plurality of 30 small openings and slots therein.

The holder shown in Figs. 13 and 14 is the holder shown at 24 or at 27 in Fig. 1, the only difference between the holders 24 and 27 being in the location thereof relative to the vertical and 35 horizontal. The holders 24 and 27 are so designed that the same will particularly direct the tear gas away from a surface against which the cover portion of the holder is clamped by the headed fastening elements 77, which pass through 40 the body portion and through the cover member and engage suitable means upon which the holders are mounted, such as the wall 29 or the bottom of the safe 22. It is not particularly desirable to obtain any appreciable forward projection of the tear gas when the holders 27 or 24 45 are used in the position shown in Fig. 1, but it is desired to project the gases at an oblique angle and at the same time diffuse or spread the same laterally as much as possible. In order to accomplish this the holder shown in Figs. 13 and 14 is 50 slightly modified from that shown in Figs. 2 to 7 inclusive, in the head portion thereof, the main body portion 61" and the main portion of the cover 70" being substantially the same as previously described in connection with Figs. 2 to 7 55 inclusive. However, the head portion 81" is of less depth than that shown in Figs. 2 to 7 inclusive, and extends at an oblique angle to the longitudinal axis of the holder and the head portion 60 83" is made deeper and of such a shape that it does not project at any point beyond the flat face of the main portion of the cover member 70".

The head portion 83" is provided with a central boss 110, which has a face 111 that is substantially perpendicular to the longitudinal axis of the tubular member 49 and which extends transversely of the openings in the forward end of the tubular member 49. A headed screw threaded fastening member 112 extends through the head portion 81" and into a screw threaded opening 113 in the boss 110. The boss 110 is so formed as to provide a partly annular groove 114 in the head portion 83", extending around on the forward side of the boss 110, and the head portion 81" 70 is provided with a plurality of small openings 115

arranged in any desired configuration and spaced to get the desired scattering effect of the gas, and a relatively large substantially elliptical opening 116 is provided in the head portion 81" at the point where the forward edge thereof meets the forward edge of the head portion 83", and this opening 116 is so located as to tend to project the gases passing therethrough in a forward direction obliquely so that the stream of gas will tend to pass downwardly and outwardly from the wall 29 in Fig. 1 and upwardly and outwardly through the door opening in the safe in Fig. 1 in the two positions shown in Fig. 1 for the holder 27 and the holder 24, the holders 27 and 24 being the same except for the positioning thereof. 15

Slots that are somewhat arcuate in shape are shown at 117 in Fig. 13 and in Fig. 14, which also are provided in order that the gases will be thrown laterally and outwardly from the wall or other member to which the holder may be secured. 20 Due to the provision of the boss 110 and the curved passage around the same there will be a centrifugal force set up by the flow of the gas around the boss, which will tend to throw the gas laterally and outwardly through the various 25 openings and slots in the device and diffuse the same as it passes out through these various openings in the holder.

A headed impaling member 118 having a screw threaded portion 119 engaging in a screw threaded 30 opening in the boss 110 is provided, which extends through a passage in the boss and which has a sharp point 120 projecting rearwardly from the wall 111 and is adapted to engage the fiber disks or other wadding that may be provided in the charge carrying member to prevent their passing out of the openings in the holder. 35

The switch base 25 is made of insulating material and has a channel 121 provided therein, through which the armored cable 127 extends. A 40 screw 122 secures the spring switch element 26 in position. Said spring switch element 26 is provided with an inwardly curved end 123, which is curled into a loop form and which, when in the position shown in Fig. 10, engages with a pair of screw contacts 124, to which the ends of the conductors 125 and 126 provided in the cable 127 are secured. Thus when the switch element is in the position shown in Fig. 10 it is in circuit closing position. In operation the switch 33 is 45 opened before the apparatus is set into operation, and the switch base 25 is fastened into position by suitable fastening elements extending through the openings 128, so that the curled or looped end 123 of the contact element 26 is in the path of the door 23 so that closing of the door will spring back the spring switch element 26, moving it away from the screw contacts 124. 50

The cable 127 has the armored covering thereof cut off of the same at a point spaced from the end thereof, leaving the conductors 125 and 126 with only the insulating material 129 covering the same at a point where an obliquely extending cutting element 130 is embedded in the base member 25 with the cutting edge 131 thereon resting against said insulating cover. The cable is free to move readily along the inclined passage 121 if a pull is exerted on the same. Normally there is a slight amount of slack in the conductors so that there will be no cutting action exerted by the blade 131. It will be noted, however, that if the cable 127 is tampered with by pulling on the same, the blade 131 will immediately cut through the insulation 129 on the conductors 125 and 126, short circuiting the switch and closing the 55 70 75

operating circuit of the tear gas protective apparatus. Of course, the switch 33 will have to be closed before this can take place, and this switch is closed after the door 23 has been closed 5 and locked, the circuit being held in open condition by the switch element 26 until an unauthorized person opens the door. Before an authorized person again opens the door 23 of the safe he first opens the switch 33 so as to prevent the 10 accidental discharge of the tear gas.

In the installation of the apparatus two pairs of conductors enter the safe, as will be evident from the circuit diagram shown in Fig. 15, in which the safe is indicated at 22 by a rectangle. 15 The short circuiting element is indicated at 130 and the tear gas guns in the holders 24, 27 and 28 are indicated by these numerals. A conductor 139 leads from one of the conductors 126 extending from the switch element 26 to the clip 44 on the 20 tear gas gun in the holder 24, and a conductor 140 is connected with the metallic casing of the holder 24, and the conductor 141 is connected with the conductor 140, the conductors 139, 140 and 141 all having slack therein, as indicated by 25 the curved portion in each thereof shown in Fig. 15. The conductor 126 leads out of the safe, as do the conductor 141, the conductor 140 and the conductor 125. The conductors 139 and 140 are provided in a cable 142, which is shown as being 30 in a slack condition in Fig. 1, and the conductors 125 and 126 being contained in a cable 127 shown as being in a taut condition in Fig. 1.

The conductors in the cable 127 and in the cable 142 are, however, spliced to conductors in 35 the cables 144 and 145 extending out of the safe, said cables extending through a conduit 146 if desired, in such a manner that a conductor 126 and a conductor 141 are located in the cable 144, whereas the cable 145 contains the conductor 125 40 and the conductor 140. The conductors 125 and 126 leading respectively from the cables 145 and 144 are both taut as installed. The conductor 125 leads to the switch 33, and a conductor 147 extends from the switch 33 to one terminal of the 45 battery 32, the conductor 140 extending to the other terminal of the battery and the conductors 140 and 147 being located in a cable 148 leading to the battery 32 from the switch 33.

The conductors 126 and 141 are provided with 50 branches 149 and 150, which lead to the holder 28, the conductor 149 leading to the clip 44 and the conductor 150 to the terminal screw 105. The conductors 126 and 141 lead into the holder 27. The discharge devices in the holders 27 and 28 55 are thus connected in parallel, the cable 144 leading to the holder 27 and the cable 103 from the holder 27 to the holder 28.

It will be seen upon reference to Fig. 15 that if 60 the switch 33 is closed and the door 23 of the safe is opened, the circuit will be completed from the battery 32 through the conductor 147, switch 33, conductor 125, the switch element 26, the conductor 126 and the conductors 139 and 140 to the fusible element 46 in the holder 24 discharging 65 the tear gas therefrom. Substantially simultaneously therewith the fusible element 46 in the holder 27 will be caused to fuse, due to the fact that the circuit thereto is completed through the conductors 147, 125, 126, 141 and 140 and switches 70 33 and 26; and also the fusible element 46 in the holder 28 will be similarly energized as it is connected in parallel with the element in the holder 27 through the conductors 149 and 150. If the conductors extending out of the safe are pulled 75 on in an attempt to disconnect the same from the

apparatus within the safe, or to pull the same far enough away from the floor, or from the safe to permit sawing thereof, any such pulling will pull the taut conductors 125 and 126 and will close the circuit in the manner described above, due to the cutting action of the cutting edge 131 of the blade 130 on the insulating covering of the conductors 125 and 126, instead of by closing the switch 26 due to opening the door 23.

If desired a foot switch 151 may also be provided at a convenient point, as in the cage shown in Fig. 1, said foot switch being utilized to operate the tear gas devices independently of the door actuated means described above, and being connected in the circuit by connecting one terminal thereof with one terminal of the battery 32 by a conductor 152, and the other terminal thereof with the conductor 126 by means of the conductor 153. A conductor 154 may also be provided connecting the other terminal of the battery with the conductor 141, although it is not absolutely necessary. The conductors 152 and 154 may be contained in a cable 155.

When the switch 151 is closed the tear gas devices will be operated even though the switch 33 is open and the switch 26 is open, as the circuit from the battery 32 will be completed through the conductor 152, the switch 151, conductor 153, conductors 126 and 149 to the tear gas devices 27 and 28 and the conductors 150, 141, and 154 to the battery, and from the conductor 126 through the conductor 139 to the tear gas device 24 and either the conductor 140, or the conductors 141 and 154, to the battery.

The foot switch or foot control 151 is preferably so made as to not be operable accidentally, but the controlling member thereof is so constructed that it is necessary to move the foot in two different directions to operate the same and the motion of the foot is a backward sliding movement in a downwardly inclined direction, thus causing any movement of the body of the operator to be such as would naturally occur in a slightly backward direction, upon being startled by the display of fire arms by a bandit, or some similar threat. This is particularly advantageous, as it prevents a forward lunging, as would occur by a mere downward pressure of the foot, which might cause a person to be shot that is attempting to operate the foot switch. The foot control device 151 comprises a base member having an inclined top wall 158 from which the side flanges 159 depend, said side flanges gradually decreasing in height, as will be evident from Figs. 16 and 21, from the height of the end flange or end wall 160 to a short curved end wall 161, which makes the bottom end of the inclined wall 158 substantially flush with the floor or other support upon which the base member is mounted, said base member being provided with a forwardly projecting perforated ear 162 for securing the same to the floor or other support, and having a pair of openings 163 in the top wall 158 adjacent the lower end thereof, through which securing elements may be passed for mounting the same on the floor or other support upon which the controlling member is located.

The top wall 158 of the base member is provided with a pair of aligned slots 164, which extend longitudinally of the same, and a longitudinally slid able controlling member or foot engaging treadle or plate 165 is provided with a pair of lugs 166, which extend through the slots 164, said lugs being elongated in the direction of length 75

of the slots 164 and fitting the same loosely, cushioning material 167 extending on both sides of the lugs 166 so as to prevent any rattling of the lugs 166 against the side walls of the slots 164 and 5 the cushioning material 167 also extending on the lower side of the upper lug 166 and on the upper side of the lower lug 166, the lugs 166 and the slots 164 being so related that the lower lug 166 reaches the end of its slot 164 in its movement 10 in an upward direction before the upper lug 166 reaches the end of its slot 164, while, when moving in a downward direction the upper lug 166 reaches the end of its slot 164 before the lower lug 166 reaches the end of its slot 164 during its 15 downward movement. It will thus be seen that the movement of the member 165 is cushioned in both directions so as to make the operation thereof silent. This is very desirable to prevent any warning reaching the bandit that a person is operating the foot control to set the tear gas discharge apparatus in operation. The cushioning material may be held in place on the lugs 166 by means of washers 168 or similar plate-like members that are secured in position by screw-threaded, headed fastening elements 169 entering said lugs 166. The slideable controlling member 165 is held out of engagement with the metallic top wall 158 of the base member by means of a plurality of inserts 170 of fibrous material, which are 20 mounted in recesses 171 provided in the top member 158 and which project above the top surface of the member 158, thus preventing any scraping noise due to movement of the slideable member 165 relative to the base member. 25

30 The member 165 is provided with converging flanges 172 at the lower end thereof, which are connected by means of a curved flange portion 173 receiving the heel of the shoe of the operator, and may be provided with suitable corrugations 174 on the upper surface thereof to prevent any slippage of the foot of the operator. The foot pedal or slideable control member 165 may also be provided with a plurality of smooth faced portions 175 to carry suitable lettering or 35 identifying data, should this be desired, which surfaces are depressed below the ribbed or corrugated surface 174.

The controlling member 165 is further provided with a pair of spaced depending lugs 176, which 40 are longitudinally aligned and operate in a slot 177 in the top wall 158 of the base member, said lugs 176 defining a groove 178 between the same, and being of such size with relation to the slot 177 as to be out of contact with the sides and 45 ends thereof during the sliding movements of the member 165 in the operation of the device.

A switch carrying bracket member 179 is 50 mounted between the side flanges 159 of the base member, being secured thereto by suitable securing elements, such as the screws 180. A toggle switch 181 is mounted in an opening in the top of the bracket 179 and extends down into said bracket, being secured thereto in any suitable manner, as by means of the screws 182, and having the tilttable operating element 183, which is 55 mounted in the groove 178 between the lugs 176. It will be obvious that if the switch is in an off position when the parts are in the position shown in Fig. 18 that a downward movement of the 60 switch 181 will throw the switch into an on position, and a return movement of the member 165 to its normal position shown in Fig. 18 will again move the switch to an off position. The end wall 160 of the base member is provided 65 with a suitable opening, through which the in-

sulating bushing 184 extends, the conductor cable 151 extending through said bushing and the conductors 152 and 153 leading from said cable into the switch 181.

The switch carrying bracket 179 is provided 5 with a transverse depending wall 185, which has an apertured ear 186 extending therefrom, into which one end of a coil tension spring 187 is hooked, the other end of the spring 187 being secured to the lower lug 166 by means of the 10 fastening element 169. A suitable member of rubber tubing or similar cushioning material is slipped over the central portion of the spring 187 for a purpose to be described below. It will be obvious that the spring 187 will be tensioned 15 upon downward movement of the member 165 and will return the member 165 to normal position upon release of the same by the foot of the operator.

A locking or latch element 189 having an arm 20 190 engaging face to face with the top surface of the top wall 158 of the base member is pivotally mounted at one end thereof on the pivot screw 191 mounted in the top wall 158. Said latch member has an upstanding flange portion 25 192 thereon at the opposite end of the arm 190 from the pivot 191, and said upstanding flange has a forward extension 193, thus providing a slot to accommodate the foot control plate 165 between said forward extension 193 and the arm 190. One side edge of the control member 165 is provided with an offset therein providing a shoulder at 194, with which the forward edge 195 of the upstanding flange 192 normally engages to prevent any sliding movement in a 30 downward direction of the slideable control member 165. The latch member 189 is held in locking position by means of a tension spring 196, which has one end thereof secured to the under side of the top wall 158 of the base by a screw-threaded securing member 197 and the other end thereof to a slightly thickened portion 198 of the member 189 by a similar screw-threaded fastening element 199.

A sleeve of rubber or similar cushioning material 200 may be passed over the central portion of the coil spring 196, the tubular members 200 and 198 being so located that the same will engage with each other in case there is any movement of the springs 196 and 187 toward each other, which might cause the same to contact and causing a noise due to scraping of the coils of the springs over each other. The side plate 159 is cut away at 201 to provide for the passage of the coil spring therethrough in the operation of the lever in its movement from the full line position shown in Fig. 17 to the dotted lines position thereof shown in said figure.

In the operation of the foot control member the operator places his foot in position with the heel of the shoe against the inclined flanges 172 and has the outer side of his foot preferably in engagement with the flange 193 on the latch, the edge of the sole of the shoe normally engaging with this flange, and a twisting movement of the foot about the heel as a pivot, in a direction such as to throw the toes outwardly, will throw the latch member in a laterally outward direction to disengage the forward edge 195 of the latch from the shoulder 194. Thereupon the foot is moved 50 in a rearward direction, that is, the foot is slid downwardly along with the member 165 by a backward movement of the foot, thereupon operating the toggle switch 181. Upon removal of the foot from the device or merely slightly lifting 55 60 65 70 75 80 85 90 95 100 105 110 115 120 125 130 135 140 145 150 155 160 165 170 175 180 185 190 195 200 205 210 215 220 225 the weight off the member 165, the switch 181 will be returned to normal position due to the action of the spring 187 in returning the member 165 to its normal position, whereupon the latch 5 will return to its normal latching position. It is obvious that any other form of switching means than the toggle switch 181 may be employed, it being preferable that a switch, operating as silently as is possible, be used for this purpose 10 so that there will be no noticeable click that might attract the attention of the bandit thereto.

What I claim is:—

1. The combination with a safe, of a tear gas discharging device in said safe, electrical means 15 for discharging the tear gas from said device including an armored conductor extending from said safe and means for discharging said device when said container is tampered with comprising means to close said circuit to actuate said electrical discharging means when a pull is exerted 20 on said armored conductor.

2. The combination with a receptacle and a closure therefor, of theft prevention means comprising a tear gas discharging device within said 25 receptacle having electrically actuated gas discharging means, closure operated means for energizing said electrically actuated means, manually operated means for rendering said closure operated means ineffective, and switching means 30 for energizing said electrically actuated means independently of both said closure operated means and the means for rendering the closure operated means ineffective.

3. The combination with a safe, of a tear gas 35 discharging device in said safe, electrical means for discharging the tear gas from said device including an armored conductor extending from said safe and means for discharging said device when a pull is exerted on said armored conductor, comprising a short circuiting cutting element 40 cutting the insulation on and bridging the conductors of an operating circuit to close the same when said conductor is pulled upon.

4. The combination with a safe and a closure 45 therefor, of a tear gas discharging device in said safe, electrical means for discharging the tear gas from said device including an armored conductor extending from said safe, means for normally changing the electrical condition of said 50 circuit to actuate said electrical discharging means comprising a switching device operated by movement of said closure out of closing position, and means for discharging said device when a pull is exerted on said armored conductor, comprising a short circuiting element bridging the 55 conductors leading to said switching device when a pull is exerted on said armored conductor.

5. In combination with a safe, of means for 60 protecting said safe comprising an electrical circuit, switching means in said safe controlling said circuit, an armored conductor extending from said switching means out of said safe, and means for closing said circuit when said conductor is pulled.

6. In combination with a safe, of means for 65 protecting said safe comprising an electrical circuit, switching means in said safe controlling said circuit, an armored conductor extending from said switching means out of said safe, and means for closing said circuit when said conductor is pulled, comprising a short circuiting element in said safe actuated when said conductor is pulled to short circuit said switching 70 means.

7. The combination with a receptacle, a closure therefor and locking means for said closure, of theft prevention means comprising tear gas discharging means within said receptacle, tear gas discharging means externally of said receptacle, means on the exterior of said closure for operating said locking means, and closure controlled means within said receptacle independent of said locking means for substantially simultaneously actuating said tear gas discharging means upon movement of said closure from closing position, said closure controlled means being inaccessible from externally of said receptacle when said closure is in closing position. 5 10

8. The combination with a receptacle, a closure therefor and locking means for said closure, of theft prevention means comprising electrically operated tear gas discharging means within said receptacle, electrically operated tear gas discharging means externally of said receptacle, means on the exterior of said closure for operating said locking means, and closure controlled means independent of said locking means for substantially simultaneously actuating said tear gas discharging means upon movement of said closure from closing position, comprising switching means within said receptacle inaccessible from externally of said receptacle when said closure is in closing position and controlling the circuit to both said discharging means to simultaneously supply electrical energy thereto. 15 20 25 30

9. The combination with a receptacle, a closure therefor and locking means for said closure, of theft prevention means comprising electrically operated tear gas discharging means within said receptacle, electrically operated tear gas discharging means externally of said receptacle, means on the exterior of said closure for operating said locking means, closure controlled means independent of said locking means for substantially simultaneously actuating said tear gas discharging means upon movement of said closure from closing position comprising switching means within said receptacle inaccessible from externally of said receptacle when said closure is in closing position, and controlling the circuit to both said discharging means to simultaneously supply electrical energy thereto, and manually operated means entirely independent of said closure operated means for rendering said switching means in said receptacle ineffective, said manually operated means comprising electrical switching means remote from said closure. 35 40 45 50

10. The combination with a receptacle, a closure therefor and locking means for said closure, of theft prevention means comprising tear gas discharging means within said receptacle, tear gas discharging means externally of said receptacle, electrically controlled means within said receptacle for actuating said tear gas discharging means upon movement of said closure from closing position, foot operated means entirely independent of said closure and externally of said receptacle for substantially simultaneously operating said internal and external discharging means independently of said switching means in said receptacle, and manually operated means for rendering said electrically operated means ineffective, comprising means independent of said locking means remote from said closure and operating independently of the operation of said closure. 55 60 65 70
